February 1, 1938. This application April 15,
1943, Serial No. 483,212

14 Claims. (Cl. 177—352)

This invention relates generally to a method and apparatus for surveying the subsurface strata of the earth by the use of artificially created seismic waves, and more particularly to the method and apparatus for recording all the data on a single spread when shot in one direction by detonating a single charge of explosive, and is a continuation of my application Serial No. 188,067, filed February 1, 1938, for Gain control for seismograph amplifiers.

In the art of exploring subsurface strata by the use of artificially created seismic waves, it is customary to detonate a charge of explosives at a point on or near the earth's surface and record the seismic waves generated by the detonation of the explosives at predetermined points removed from the point of generation. From the data thus recorded it is possible to ascertain the depth of subsurface horizons, from which the seismic waves that are recorded have been reflected. The depths of these subsurface horizons are computed from the velocity and time required for these seismic waves to travel down to the reflecting horizon and return to the detecting instrument. This velocity will vary, dependent upon the density and elastic coefficients of the materials through which it travels. In addition to considering the velocity at which reflected waves will travel in subsurface strata, it is necessary to consider the velocity of their transmission through the unconsolidated, weathered, sedimentary surface of the earth.

The usual procedure when the exploration of an area is begun is to develop these velocities in the different strata by what is termed a "velocity program" which entails recording records of seismic waves which will give directly the velocities in these particular strata. After having once ascertained these velocities, they can be used throughout the area in computing the depth of the particular reflecting strata. Due to the fact that the weathered surface layer of the earth varies in thickness, it is necessary that the thickness of this weathered layer be computed for each spread or location of geophones. To obtain the data from which the thickness of the weathered layer is computed, charges of explosives are detonated at the selected shot points and the velocity of the wave travel through the weathered or surface layer is determined. Due to the fact that the wave in which we are first interested travels substantially in a direct route to the detector, there is very little absorption present and an impulse of great amplitude is recorded. It is necessary that the gain in amplification of a vacuum tube amplifier be at the maximum in order that the

break in the seismogram trace, resulting from the arrival at the geophone of the first impulse of energy, be very definite. As a consequence heretofore, it has been necessary to record these data on a separate seismogram from that on which reflected waves are recorded. Such a procedure would necessitate recording a plurality of seismograms to obtain the data in the weathered layer and records of the reflected waves from shallow subsurface strata. Since the high cost of field operations makes the time factor of paramount importance, it is desirable to record all of these data on a single record of standard width from the detonation of a single charge of explosives. Such a procedure would result in tremendous savings in the amount of explosives required and in the time required by the field party to record the data necessary on a single spread, as well as the time required for an interpreter to observe the data on a plurality of seismograms.

With previous methods of recording these data by the use of a plurality of charges of explosives, from which seismic waves have been recorded on a corresponding number of seismograms, it has been almost impossible to duplicate the conditions under which each charge of explosive is detonated, due to several factors, the most important of which being the changes in the conditions affecting the medium in which the shot is planted. When one charge of explosives is detonated in the bottom of a shot hole, a pocket or cavity is formed in some formations, while in others the bottom of the hole is filled up, due to the fact that the medium forming the walls of the cavity is of loosely packed material. This sometimes results in a loss of as much as 10' in the depth of the hole, and, in extreme cases, where the bottom of the hole is in a quicksand material, as much as 20' or 30' of the hole are lost by the detonation of a single charge in it. Such changes in conditions under which successive charges of explosives are detonated introduce variable factors in the apparent velocities of the recorded waves. These variable factors would make profiles computed from these data in error.

Therefore, the primary object of this invention is the provision of a method and apparatus whereby all the data that is required to be recorded on a particular spread when shot from one direction can be recorded on a single seismogram.

Another object of this invention is in the provision of a method and apparatus for controlling the gain in amplification to effect a definite recording of first impulses and reflected waves from shallow as well as deep horizons.

Still another object of this invention is in the provision of means whereby the vacuum tube amplifier is allowed to remain at or near its maximum sensitivity until the first impulse of the direct traveling waves has been recorded; then instantaneously suppressing the gain in amplification and allowing it to expand exponentially with time.

This invention further contemplates means whereby the suppression of the gain in amplification can be initiated by the impulse delivered to the geophone by the direct traveling waves.

This invention has for another of its objects the provision of means whereby the suppression of the gain in amplification can be initiated by the electrical impulse that is received and recorded at the instant of detonation of the charge of explosives.

Still another object of this invention resides in the provision of a method for controlling the gain in amplification in a predetermined manner, without sacrificing any of the available gain present in the amplifier at the time the first impulses are recorded from direct traveling waves or at the time the latest reflected waves are recorded.

Still another object of this invention is in the provision of a means for initiating the predetermined control which can be accomplished automatically by the operation of a gaseous discharge tube, or by relay, or manually by switch.

This invention also contemplates the provision of means which will operate on either the control or suppressor grid of a conventional vacuum tube in one or more stages of the conventional amplifier to effect the above mentioned results.

Another object of the invention is in the provision of a unit for effecting these results which can be utilized with a conventional amplifier.

Still another object of the invention resides in the provision of a unit which will operate with low energy consumption.

Other objects and advantages will become apparent from the following detailed description, when considered with the attached drawings, in which:

Figures 1a and 1b, placed end to end, illustrate a seismogram recorded in the conventional manner;

Figures 2a and 2b similarly illustrate a seismogram of the type that can be recorded by the method and with the apparatus of this invention;

Figures 3a and 3b, placed end to end, illustrate a voltage wave that would result from passing a wave of constant amplitude through an electric seismograph amplifier employing the control forming the subject matter of this invention;

Figure 4 is a curve which has been plotted with gain in amplification as ordinates and time as abscissae representing the instantaneous values of gain in amplification in recording a seismogram such as is illustrated in Figures 2a and 2b;

Figure 5 is a fundamental electric circuit illustrating the principles employed in the development of the control for vacuum tube amplifiers that forms the subject matter of this invention;

Figure 6 is a curve that has been plotted with condenser charging current as ordinates and time as abscissae;

Figure 7 is an illustration of the fundamental circuit described above when used to control the

grid potential of a vacuum tube in a conventional amplifier;

Figure 8 is the circuit diagram shown in Figure 7 showing additionally the use of a gas triode vacuum tube for the purpose of initiating the operation of the control;

Figure 9 is a partial block diagram of an electric seismograph showing the application of the circuit forming the subject matter of this invention to a conventional amplifier.

Referring to the drawings in detail, particularly Figures 1a and 1b there is illustrated a seismogram which shows the manner in which the direct traveling waves, as well as the reflected waves, from five geophones or detectors are conventionally recorded on a single seismogram. The transverse lines indicate definite and equal small intervals of time, such, for example, as .01 second. It will be noted that there is an indication known in the art as a time break on the middle trace at X indicating the instant at which the charge of explosive was detonated. The period of time elapsing between the instant at which the charge was detonated and the arrival of the waves generated thereby at the geophone is represented by the number of spaces and fractions thereof between the indication X, denoting the time break or instant of explosion, and the point where a discontinuity occurs on the respective traces. To record a record such as that illustrated the charge of explosive and the five geophones are located in the same vertical plane and the geophones are equidistantly spaced one from the other. The discontinuity in the respective traces is indicative of the instant at which the first energy strikes the geophone. Although this first initial impulse is generated by direct traveling waves of abrupt wave front, there are many other waves of different frequencies and velocities that follow the wave which delivers the initial impulse to the detector. Due to the fact that these direct traveling waves are of so much greater amplitude than reflected waves, their attenuated wave train would tend to obscure reflected waves from shallow horizons that would arrive at the geophone or detector a relatively short interval of time after the first impulse. As shown by the illustration in Figures 1a and 1b, it is impossible to distinguish any of the reflected waves from shallow horizons, from direct traveling waves. This is partly due to the fact that the direct traveling waves completely obscure the reflected waves, and partly due to the fact that there is less absorption and resulting loss of energy in waves which have been reflected from shallow horizons than those which have been reflected from deep horizons. From this it readily becomes apparent that some means must be provided for controlling both the amplitude of the direct traveling waves after the first impulse has been recorded and the amplitude of reflected waves from shallow horizons. Such control of amplification is illustrated in Figures 2a and 2b. These figures illustrate a seismogram such as would be recorded by the method and apparatus forming the subject matter of this invention. In this illustration it will be noted that the first arrival of energy to the detector or geophone is recorded on the seismogram at an amplitude corresponding to that disclosed in Figure 1a. Additionally, it will be noted that, after the last first break has been recorded, the gain in amplification in all amplifiers has been suppressed to some small value, which, in some cases, can be zero. Then, from this point the gain in am-

plification as produced by the amplifier expands exponentially with time, resulting in a record that is uniformly trimmed, showing reflections which have been recorded with almost constant amplitude from horizons as deep as it is practical to correlate or profile. In some areas the weathered layer or overlying unconsolidated stratum is relatively thin and reflections are obtainable from shallow horizons underlying the weathered layer. If it is impossible to instantly suppress the gain in amplification after the direct traveling waves have been recorded, these shallow reflections will be completely obscured. Therefore, the utility for this particular response is readily apparent. A record such as that illustrated in Figures 2a and 2b in addition to giving definite data from which the thickness of the weathered layer can be checked at each spread, also gives the reflections from all horizons that it is desired to work or profile. Since these are all the data that are required from seismic waves which have been recorded in one direction on a particular spread, there is no necessity for detonating more than one charge of explosive and recording more than one seismogram. This obviously results in a tremendous saving of time, explosives, and a saving in depreciation of the equipment.

To obtain a seismogram such as that illustrated in Figures 2a and 2b, it is desired that the amplification characteristic of the electric or vacuum tube amplifier be as disclosed in Figures 3a and 3b and in Figure 4 in which there is shown a curve having the gain in amplification as ordinates plotted against time as abscissae.

A fundamental electrical circuit which may be used in connection with the control or suppressor grid of a conventional vacuum tube in one or more stages of a vacuum tube amplifier, is shown in Figure 5. This circuit, although a simple circuit, serves very well to illustrate the fundamental principles of this invention. In this circuit there is illustrated, connected in series, a source of potential 1, a resistance 4, a condenser 5 and a switch 2. Then, connected in parallel with the series combination of resistance 4 and capacity 5, there is a second resistance 3. At the point 6 in the circuit a ground wire is attached, bringing this point in the circuit to zero potential. When the switch 2 is closed, a source of potential 1 will cause a current to flow in the circuit through the resistance 4 until the condenser 5 is fully charged. The intensity of the current flowing during the charging process of the condenser 5 and the time required for the condenser to become fully charged is determined and controlled by the value of the resistance 4, the capacity of the condenser 5, and the potential of the battery 1. When the switch 2 is closed, the current I begins to flow at its maximum value and decreases to zero, in the manner well known in the art and illustrated in Figure 6, and the condenser 5 becomes fully charged. The charging time for the condenser 5 is controllable by the resistance 4. From the fundamental elements of electric circuits it is well known that a current flowing through a resistance is in time phase relationship with the voltage across the resistance. Consequently, the IR drop across the resistance 4, while the condenser 5 is charging, has similar characteristics to that of the current flowing through it. Therefore, the potential at the point B with respect to the point 6, which is grounded, goes through the same values relative to time that the IR drop across the resistance 4 does. That is, this potential will go from zero value to its maxi-

mum negative value instantly, and then from its maximum negative value to zero exponentially with time. In order to complete a discharge circuit for the condenser 5, a resistance 3 is connected as described above and shown in Figure 5. This discharge circuit becomes effective to restore the circuit to original conditions and makes it ready for a repetition of the cycle described above when the switch 2 is open.

10 The varying potential at the point B can be utilized as a variable grid bias voltage on a vacuum tube in an electric seismograph amplifier. It is well known that the gain in amplification produced by a vacuum tube can be controlled by varying the grid bias voltage. Additionally, it has been found that if a sufficiently large negative value of voltage is impressed across the grid of a vacuum tube, it can be biased completely out of its characteristic and no appreciable gain can be obtained from that tube. Dependent upon the type and make of a particular vacuum tube used for purposes of amplification in an amplifier, it will function to produce the greatest gain at a zero grid potential or some small negative value of grid bias voltage. Additionally, it has been found that by varying this grid bias from a zero or small negative value to a relatively large negative value, the amplification can be reduced proportionally, and this principle is utilized in controlling the instantaneous values of gain in amplification in the seismograph amplifier.

In Figure 7 there is shown this fundamental circuit connected to the control grid of a conventional vacuum tube of a conventional amplifier.

35 The simple circuit explained above has now been modified in that the resistance 4 has been divided into two variable resistances 4 and 7 in series. The point B is made variable on the resistance 4 in order to select the desired negative potential 40 and the point A is made variable in order to control the charging time for the condenser 5. By connecting the point B to the control grid of a vacuum tube, the variable potential described above can be utilized to control the gain in amplification of this vacuum tube. Additionally, if the battery 8 is connected in series with the point B and the control grid of a vacuum tube 9, one is enabled to control the initial and/or maximum grid bias voltage, which, in turn functions to 45 control the gain in amplification produced by the tube 9. As described above, when the switch 2 in this circuit is closed, the point B is immediately placed at a negative potential with respect to the ground 6. This negative potential is selected sufficiently large that the grid is biased out of the characteristic of the tube sufficiently far to reduce the gain in amplification to a predetermined value. This is effected instantly on closing the switch 2. As the condenser 5 approaches full charge, the current in the resistances 4 and 7 approaches zero, and the potential from the ground, of the point B as a result approaches zero, causing the grid bias voltage on the tube 9 to assume the initial value. The position of the point A on the resistance 7 can be so adjusted as to control the time required to assume these conditions. The small initial value of grid bias remaining on the tube can be controlled by the position of the contactor B on the 55 variable resistance 4. Controlling the grid bias on the tube 9 in this manner will produce an amplification curve, as shown in Figure 4. This curve is plotted with gain in amplification as ordinates and time as abscissae, and represents 60 instantaneous values of amplification throughout 70 75

the time required to record a record, such as that disclosed in Figures 2a and 2b. Comparing the curve to the seismogram illustrated in Figures 2a and 2b, it will be noted that between the points G and H on the curve, the gain in amplification is at a constant predetermined value. This period of time represents the time required for the initial breaks due to the direct traveling seismic waves to be recorded. At the instant at which the last initial break occurs on the trace from the geophone most distant from the shot, the gain in amplification immediately drops to a value represented by the point K. This drop in gain of amplification occurs instantly with the closing of the switch 2 discussed above. Dependent upon the value of the resistances 4 and 7, the capacity of the condenser 5 and the magnitude of the potential 1, the gain in amplification is then caused to expand exponentially with time as the condenser 5 is fully charged during an interval of time corresponding to the distance between the points K and L on the curve.

In Figure 8 there is illustrated a circuit which corresponds to that in Figure 7, with the exception that the operation of the circuit to control the gain in amplification of the vacuum tube 9 is initiated by a gas triode tube 13, such as the tube commonly sold on the market under the trade-name of "Thyratron." The characteristics of a vacuum tube of this type are well known to one skilled in the art; that is, that a grid placed between a cathode and anode of a hot cathode tube containing gas, if sufficiently negative, will prevent the arc from striking, because under these conditions, there is no accelerated field around the cathode. The electrons, therefore, cannot acquire sufficient velocity to ionize. When the grid is made positive, electrons are accelerated toward it. They collide with gas atoms, ionizing them and the arc strikes. Therefore, it can be seen that a negative grid prevents the arc from striking, and a positive grid allows it to strike, effecting a flow of current from the cathode to the anode of the tube.

After the arc has struck, it presents the peculiar feature that the grid has no more control of it, and the current will continue to flow until the plate circuit is broken. As shown, the grid is negatively biased with respect to its cathode by the bias battery C.

The arc in the gaseous discharge tube can be caused to strike in many ways. For example, the impulse of current flowing in the blaster circuit that is depended upon for the time-break signal, can be used to change the grid bias voltage of the gaseous discharge tube from a large negative value to a positive or small negative value, or the initial impulse of the wave train after sufficient amplification, can be used for the same purpose. In other words, a potential from any source, just so long as it has a sufficiently high positive value, can be used to initiate the flow of current in the plate circuit of the gaseous discharge tube.

After the arc is struck in the tube, the current from the battery 1 or plate supply source which flows in the plate circuit causes an IR drop across resistance 3. This IR drop is impressed across the resistances 4 and 7 and condenser 5 in series, which charges condenser 5, and during the process of charging condenser 5, produces an IR drop across resistances 4 and 7.

In addition to the use of the gas triode 13 described above in completing the charging circuit for the condenser 5, switches 10 and 11 are pro-

vided. Switch 10 is used for opening the gas triode plate circuit, to stop the flow of current in the plate circuit, for it is a characteristic of the gas triode tube that once the arc is struck, the grid 5 has no more control. Switch 11 is used for removing the bias manually from the grid of the gas triode tube to cause current to flow in its plate circuit for test purposes. A resistance 11a is included in the circuit completed by switch 11. After all adjustments have been made and a seismogram is to be recorded, the normal position for the switch 10 is closed and the switch 11 is open.

When a positive potential resulting from an impulse is impressed on the grid of the gas triode tube to reduce the negative bias from battery C, the full plate current starts to flow instantly. This plate current develops an IR drop across the resistance 3 instantly. This IR drop is also impressed across the resistances 4 and 7 and condenser 5, that is connected in series with them. This results in the point B going instantly to a maximum negative value with respect to the ground 6. Since the control grid has this value of IR drop impressed upon it, the gain in amplification instantly drops to a predetermined value. Then, as the current continues to flow through the resistances 4 and 7, the condenser 5 will become fully charged and the gain in amplification, controlled by the IR drop in the resistance, will increase exponentially with time.

In Figure 9 there is shown a further modification of this invention, in that the fundamental circuit is used to control the grid bias voltage on vacuum tubes in a plurality of amplifiers. In this illustration, of the circuit diagram the potential at point B through the resistances 12 is applied to the grids of one or more vacuum tubes in a plurality of amplifiers. The resistances 12, in addition to serving as means whereby a connection 40 to a plurality of amplifiers can be made, are made variable so that the maximum gain in amplification for each amplifier can be controlled independently of the others.

The battery 15 in this circuit is used to adjust 45 the initial and/or maximum amplification of all the amplifiers controlled. The potential of the battery 8, by means of the variable resistances 12, is used to control the initial and/or maximum gain in amplification of the individual amplifiers. With 50 such an arrangement it is possible to record on one seismogram several traces having equal amplitudes throughout their length.

Although the illustrative circuits by which the control of the amplifier is accomplished, are described in connection with the suppressor grid of a conventional vacuum tube, it is obvious that equal or even better control can be had by applying this principle to the ordinary control grid of three element tubes.

Referring to Figure 9, the operation of this system is as follows: A signal such as that delivered by the impulse recorded on the last trace of the seismogram due to direct traveling waves is conducted through the conductor 14 to the transformer T and is impressed upon the grid of a gas triode tube 13, which has been adjusted to some negative value. Assuming that the switch 10 is closed when this impulse is impressed upon the grid of the gas triode, the arc will be struck, due 70 to the fact that the grid has been made sufficiently positive to cause it to lose control. A flow of plate current results through the circuit, which will in turn flow through the resistances 4 and 7 to charge the condenser 5. At the time the plate current begins to flow in the plate circuit of this

tube, the point B immediately assumes its maximum negative value of potential relative to the ground 6. This value of negative potential is due to the IR drop in the resistances 4 and 7. As the condenser 5 becomes charged, the current passing through the resistances 4 and 7 will decrease, resulting in a decrease in the IR drop across these resistances. Thus it can be seen that the potential at the point B will go from some maximum negative value to ground potential at the time the condenser 5 becomes fully charged. This variable potential produces a change in the grid bias on the vacuum tube 9. There will result a corresponding change in the gain in amplification. In Figure 4, the instantaneous values of amplification, from the instant at which the time break occurs until the entire seismogram is recorded, are illustrated. Utilizing a system having a characteristic curve of this nature will produce a seismogram such as that illustrated in Figures 2a and 2b. A study of this seismogram will indicate that no more than one record is required to record all the data necessary on a profile that is shot in one direction.

In Figure 9 it will be noted that by connecting the conductors 14 to the time break and telephone circuit that the operation of this circuit can be initiated by the time break. With the circuit in an electric seismograph connected in this manner it will function as an ordinary expander at the time the time break impulse is received at the transformer T. The grid of the gas triode 13 will immediately lose control and plate current will begin to flow. As described above, this plate current will develop a large IR drop across the resistances 4 and 7 to place a relatively large negative bias upon the vacuum tube 9 in the conventional amplifier shown. This results in a suppression in the gain in amplification instantly to some predetermined value. As this occurs the gain in amplification is then allowed to build up exponentially with time as the condenser 5 becomes fully charged.

Although specific arrangements of elements are herewith described, it is obvious to those skilled in the art that other arrangements of elements in an electric circuit would produce the same result. Although the circuit of Figure 9 shows the control acting on a grid of one tube, it is equally adaptable to the control of the grids of more than one tube of a seismograph amplifier.

I claim:

1. Apparatus for making records of seismic waves generated at a shot-point and received at a station remote therefrom, comprising a seismometer at the said station adapted to convert said waves into electro-motive-forces of voltages indicative of the amplitude and in sympathy with said waves, an amplifier for magnifying said voltages, a galvanometer-recorder for recording the same in respect to time intervals, and means responsive only once during the receipt of said waves to an amplifier output above a predetermined minimum value, to reduce the gain of said amplifier, and means to gradually return said gain to normal over a period of the order of the duration of the waves.

2. Apparatus for making records of seismic waves generated at a shot-point and received at a station remote therefrom, comprising a seismometer at the said station adapted to convert said waves into electro-motive-forces of voltages indicative of the amplitude and in sympathy with said waves, an amplifier for magnifying said voltages, a galvanometer-recorder for recording

the same in respect to time intervals, means responsive only once during the receipt of said waves to an amplifier output above a predetermined minimum value, to reduce the gain of said amplifier, means to gradually return said gain to normal over a period of the order of the duration of the waves, and means to adjust the rate of return of said gain to normal.

3. Apparatus for making records of seismic waves generated at a shot-point and received at a surface station remote therefrom, comprising a seismometer at the said station adapted to convert said waves into electro-motive-forces of voltages indicative of the amplitude and in sympathy with said waves, an amplifier for magnifying said voltages, a galvanometer-recorder for recording the same in respect to time intervals, means responsive only once during the receipt of said waves, to an amplifier output which is greater than a predetermined value, to reduce the gain of said amplifier, means to gradually return said gain to normal over a period of the order of the duration of the waves, and means to non-linearly change the rate of return of said gain to normal.

4. A recording system for seismic waves occurring in a train extending over a period of several seconds in which the first part of the train has a general amplitude level several times greater than that of the remainder and in which the general level of the remainder gradually decreases, comprising in combination, a detector for converting said waves into voltages indicative of the amplitude and in sympathy with said waves, an amplifier for said voltages associated with said detector, a recorder connected to the output of said amplifier, said amplifier including a tube having a control element, a control tube having a control element associated with said output and a cathode, a source of negative bias voltage for said second mentioned element having its positive side at cathode potential and being adjusted in value to prevent current flow in the anode circuit of the control tube until said output exceeds a predetermined value, a resistor in the said anode circuit the drop across which increases the amount of negative bias on said amplifier tube control element when current flows through the resistor, and means in said anode circuit to effect an initial high current flow through the resistor followed by a gradual diminution in the current.

5. In methods of seismograph prospecting wherein a series of seismic vibrations of amplitude initially high and decreasing with time are detected, converted into electrical signals and the signals are amplified electrically and recorded, and the amplification gain is controlled by a controller supplied with signal energy and of such character that on supply thereto of such energy the controller acts to lower the gain and thereafter gradually and progressively restores the gain: the improvement which comprises cutting off the effect of the signal energy on the gain controller immediately after receipt of the initial high amplitude signals and keeping such effect cut off throughout receipt of the remainder of the series of vibrations, whereby the gain increases smoothly without falling off to lower values, subsequent to receipt of the initial high amplitude signals, uninfluenced by subsequent fluctuations in amplitude of signal energy.

6. An apparatus for seismic prospecting comprising a detector of seismic waves adapted to convert said waves into electrical signals; a

thermionic tube amplifier for amplifying said electrical signals, said tube amplifier having a control grid; a recorder for recording said electrical signals in correlation with time; a control circuit including a Thyratron tube, a resistance and a condenser in series in the plate circuit of said Thyratron tube; means for impressing a negative bias on the control grid of said amplifier upon the flow of current in said plate circuit whereby the gain of said amplifier is reduced substantially instantaneously upon the flow of current in said plate circuit and is gradually restored upon the completion of the charging of said condenser; a control grid for said Thyratron tube; means for normally biasing said Thyratron control grid to prevent the flow of current in the plate circuit of the Thyratron tube; and means for reducing the bias on said Thyratron control grid to permit the flow of current in said Thyratron plate circuit.

7. An apparatus for seismic prospecting comprising a detector of seismic waves adapted to convert said waves into electrical signals; a thermionic tube amplifier for amplifying said electrical signals, said tube amplifier having a control grid; a recorder for recording said electrical signals in correlation with time; a control circuit including a Thyratron tube, a resistance and a condenser in series in the plate circuit of said Thyratron tube; means for impressing a negative bias on the control grid of said amplifier upon the flow of current in said plate circuit whereby the gain of said amplifier is reduced substantially instantaneously upon the flow of current in said plate circuit and is gradually restored upon the completion of the charging of said condenser; a control grid for said Thyratron tube; means for normally biasing said Thyratron control grid to prevent the flow of current in the plate circuit of the Thyratron tube; and means responsive to the initial output of signals from said amplifier for reducing the bias on said Thyratron control grid to permit the flow of current in said Thyratron plate circuit.

8. Apparatus for seismic prospecting comprising a detector of seismic waves adapted to convert said waves into electrical signals; a thermionic tube amplifier to amplify the electrical signals, said tube amplifier having a suppressor grid; a recorder to make a record of said electrical waves in correlation with time; a control circuit including in series a condenser, a resistance, a source of current and a Thyratron tube; a connection between said suppressor grid and said circuit to impose a negative bias on said grid when the circuit is initially closed by the striking of an arc across said Thyratron and thereby substantially instantaneously reduce the gain of said thermionic tube amplifier, said negative bias gradually decreasing with the reduction in the current in said circuit as said condenser becomes charged and thereby gradually restoring the gain of said thermionic tube amplifier; and means responsive to the seismic operations for causing an arc to strike across the Thyratron tube.

9. Apparatus for seismic prospecting comprising a detector of seismic waves adapted to convert said waves into electrical signals; a thermionic tube amplifier to amplify the electrical signals, said tube amplifier having a suppressor grid; a recorder to make a record of said electrical waves in correlation with time; a control

circuit including in series a condenser, a resistance, a source of current and a Thyratron tube; a connection between said suppressor grid and said circuit to impose a negative bias on said grid when the circuit is initially closed by the striking of an arc across said Thyratron and thereby substantially instantaneously reduce the gain of said thermionic tube amplifier, said negative bias gradually decreasing with the reduction in the current in said circuit as said condenser becomes charged and thereby gradually restoring the gain of said thermionic tube amplifier; a resistance shunted across the condenser and the resistance of said circuit for the discharge of the condenser; and means responsive to the seismic operations for causing an arc to strike across the Thyratron tube.

10. An apparatus for seismic prospecting comprising a detector of seismic waves adapted to convert said waves into electrical signals, a thermionic tube amplifier for amplifying said electrical signals, said amplifier having a control grid, a recorder for recording said electrical signals in correlation with time, a control circuit for said amplifier including a resistance and a condenser in series, means for applying a potential difference across said series-connected resistance and condenser thereby to produce current flow through said resistor which is initially of high magnitude and as said condenser is charged is gradually reduced, and means for applying to said control grid a negative bias derived from the potential difference produced across said resistance by the current flow therein, whereby the gain of said amplifier is reduced substantially instantaneously upon the flow of current through said control circuit and is gradually restored upon the completion of the charging of said condenser.

11. An apparatus for seismic prospecting comprising a detector of seismic waves adapted to convert said waves into electrical signals, a thermionic tube amplifier for amplifying said electrical signals, said amplifier having at least one gain-controlling grid, a recorder for recording said electrical signals in correlation with time, a control circuit for said amplifier including a resistance and a condenser in series, means operable during receipt of said waves for applying a potential difference across said series-connected resistance and condenser thereby to produce current flow through said resistor which is initially of high magnitude and as said condenser is charged is gradually reduced, and means for applying to said control grid a negative bias derived from the potential difference produced across said resistance, whereby the gain of said amplifier is reduced substantially instantaneously upon the flow of current through said control circuit, and is gradually restored to its original value upon the completion of the charging of said condenser.

12. In an apparatus for seismic prospecting having a detector of seismic waves adapted to convert said waves into electrical signals, a thermionic tube amplifier for amplifying said electric signals, said amplifier having at least one gain-controlling grid and a recorder for recording said electrical signals in correlation with time, the combination of means for controlling the amplification of said amplifier comprising a control circuit including a resistance and a condenser in series, means operable at a predetermined time for applying a substantial potential difference to said control circuit to produce a current flow therein which is initially of

high magnitude and which decreases with the charging of said condenser, means for producing on said gain-controlling grid of said amplifier a negative bias whose magnitude varies with that of said current flow, thereby quickly to reduce by a substantial amount the gain of said amplifier and thereafter gradually to increase the amplification to its initial value upon the completion of the charging of said condenser.

13. In an apparatus for seismic prospecting having a detector of seismic waves adapted to convert said waves into electrical signals, a thermionic tube amplifier for amplifying said electric signals, said amplifier having at least one gain-controlling grid and a recorder for recording said electrical signals in correlation with time, the combination of means for controlling the amplification of said amplifier comprising a control circuit including a resistance and a condenser in series, means operable at a predetermined time during the detection of said waves for applying a substantial potential difference to said control circuit to produce a current flow therein which is initially of high magnitude and which decreases with the charging of said condenser, means for producing on said gain-controlling grid of said amplifier a negative bias whose magnitude varies with that of said current flow, thereby quickly to reduce by a predetermined amount the gain of said amplifier, and thereafter gradually to increase the ampli-

fication to its initial value upon the completion of the charging of said condenser.

14. In an apparatus for seismic prospecting having a detector of seismic waves adapted to convert said waves into electrical signals, a thermionic tube amplifier for amplifying said electric signals, said amplifier having at least one gain-controlling grid and a recorder for recording said electrical signals in correlation with time, the combination of means for controlling the amplification of said amplifier comprising a control circuit including a resistor and a condenser in series, means for applying a substantial potential difference to said control circuit to produce a current flow therein which is initially of high magnitude and which decreases with the charging of said condenser at a predetermined rate fixed by the capacity of said condenser and the resistance of said resistor, means for producing in response to said current flow a negative bias on said gain-controlling grid of said amplifier thereby quickly to reduce by a predetermined amount the gain of said amplifier, and thereafter gradually to increase the amplification to its initial value upon the completion of the charging of said condenser, and means for adjusting the extent of said reduction in amplification without changing the resistance of said resistor in series with said condenser.
